UNITED STATES PATENT OFFICE.

BRUNO URBAN, SR., OF LUDWIGSHAFEN-ON-THE-RHINE, GERMANY.

HOUSE CONSTRUCTION OF TUBES OR TUBULAR MEMBERS.

Application filed June 14, 1926, Serial No. 115,827, and in Germany May 1, 1926.

This invention relates to a house-construction of steel tubes or the like presenting, in comparison with the known building constructions, the advantage that the building 5 of the house is facilitated and that the house is of lighter weight but nevertheless much more resistant.

According to the invention the skeleton of the house is preferably composed of four-cornered thin-walled steel-tubes, which might be also of triangular or multiple-cornered cross section, the horizontal tubes being placed on edge and said tubes are connected with one another by butt-straps of 10 convenient type, the vertical construction elements being preferably arranged so that they ride upon said horizontal tubes with which they are connected by butt-straps. Herefrom results a construction which is 15 capable to resist several times greater loads than similar constructions of known type, this resisting capability being further increased by a flat-iron bar standing on edge.

The parts of the building elements can 20 be connected in longitudinal direction by butt-straps, sleeves or the like or by being telescoped in any convenient manner.

The walls of the building consist preferably of commonly used plates which are 25 connected with the skeleton by screws or in another convenient manner. Between the outer and the inner wall an insulating layer 30 is arranged at a certain distance from the outer and from the inner wall, said insulating layer rendering the building sound-proof. The plates may be specially impregnated 35 to make them fire-proof, so that in this manner a sound-proof and warm wall, capable to resist any influence of the weather 40 is obtained.

The resisting capability of the plates can be considerably increased by insertions of wire gauze embedded in the plates at the manufacturing.

An embodiment of the invention is illustrated, by way of example, in the accompanying drawing in which:

Fig. 1 shows how the skeleton rests upon the foundation.

Fig. 2 shows a connection-joint by means of butt-straps.

Fig. 3 shows in horizontal section one corner of two adjacent walls.

Fig. 4 is a similar view showing a partition.

Fig. 5 shows in cross section a portion of the cellar ceiling.

Fig. 6 is a similar view showing a portion of the ceiling of a room.

Fig. 7 shows a cross-butt-strap connection. 60

Fig. 8 shows in perspective view the complete structure of a house.

The horizontal frame *a* is placed upon the foundation *b* in such a manner that the tubes, of which the frame is composed, are 65 embedded in the foundation standing on edge, so that shifting-moments are absolutely excluded. The horizontal and vertical members *c*, *d* joining the horizontal frame *a* are fixed on this frame by means of 70 butt-straps *e*, the members having previously been clamped on the horizontal frame.

The corner of a house, Fig. 3, comprises preferably several vertical members *d*, the intervals between said members being filled 75 with wooden bars *f* designed to serve for the fixation of the outer wall *g* and of the inner wall *h*.

The central or intermediate insulating layer *i* is at its ends shaped in accordance 80 with the corners of the member *d* so that it is securely fixed. The intervals *k* between the intermediate layer *i* and the outer and inner walls *g* and *h* serve to render the walls 85 of the building sound-proof. Several plates are connected with one another by means of dowels *l*.

As shown in Fig. 5, the ceiling of the cellar is constructed in such a manner that the horizontal members *c* are completely 90 embedded in concrete *o*, which concrete is covered by a convenient layer *m*. The ceiling of a room, Fig. 6, may be constructed like a coffered ceiling. At points where the elements of the frame or of the members 95 cross one another the cross-butt-strap *m*, shown in Fig. 7, is preferably used.

I claim:

1. A house construction of tubes or tubular members, comprising in combination with the foundation, a horizontal supporting frame of steel tubes placed on edge, vertical members, horizontal members, and butt-straps for connecting said horizontal and vertical members with said supporting frame 100 to form a skeleton of considerable carrying-capability. 105

2. A house construction of tubes or tubular members, comprising in combination with the foundation, a horizontal support- 110

ing frame of steel tubes placed on edge, vertical members, horizontal members, and butt-
straps for connecting said horizontal and
vertical members with said supporting
frame to form a skeleton of considerable
carrying capability, and walls in said skele-
ton consisting of an inner and an outer wall
made from plates, and of an intermediate

layer of convenient material arranged be-
tween said inner and outer walls so that an ¹⁰
interval remains between said inner layer
and said outer and inner walls, and dowels
for connecting said plates with one another.

In testimony whereof I affix my signature.

BRUNO URBAN, SEN.
